UNITED STATES PATENT OFFICE.

REUBEN T. PALMER, JR., AND FREDERIC W. MERCER, OF NEW LONDON,
CONNECTICUT, ASSIGNORS TO THE R. T. PALMER COMPANY, OF SAME
PLACE.

SLITTING AND REWINDING MACHINE.

SPECIFICATION forming part of Letters Patent No. 538,463, dated April 30, 1895.

Application filed July 9, 1894. Serial No. 517,029. (No model.)

To all whom it may concern:

Be it known that we, REUBEN T. PALMER, Jr., and FREDERIC W. MERCER, citizens of the United States, and residents of the city 5 and county of New London, State of Connecticut, have invented certain new and useful Improvements in Slitting and Rewinding Machines, which improvements are fully set forth and described in the following specification, reference being had to the accompanying sheet of drawings.

The particular office of this class of machines is to convert large rolls of paper or like material, in web form, into a number of similar rolls of equal or less diameter, of ribbon form.

The object of our invention is to provide a machine for doing automatically the work just described, that shall be of simple construction and that may be cheaply produced.

Our machine embraces mechanism, which, when in operation, serves to unwind the web of stock from its original large roll, to feed the same forward to be slit into strips of 25 desired width and finally to rewind said strips evenly into compact rolls of desired diameter, thereby leaving said stock in convenient form to be readily handled or used by paper-box makers, bookbinders, &c.

To assist in the explanation of our invention we have provided the accompanying sheet of drawings, in which--

Figure 1 is a side elevation of our machine, and Fig. 2 is a plan view of the same. Fig. 3 35 illustrates, on a somewhat enlarged scale, a portion of the rewinding mechanism; and Fig. 4 shows, on a similar scale, certain circular saws or cutters which compose the slitting mechanism of our machine.

While a machine of this class is desirable for use in connection with rolls of different kinds of material it is especially useful in slitting up large rolls of paper and throughout the remainder of this specification we 45 have described our machine as so used; but we do not wish to be understood as confining our machine to this use exclusively.

Referring to the drawings the letters "a" and "b" denote the side frames of our machine and "c" the main or driving shaft suit-

ably journaled in said frames and at right angles thereto. Said shaft bears upon one end a driving pulley "d" and on its opposite end a pulley "e" whose face is of considerable width for a purpose hereinafter explained.

Located approximately over the main shaft "c" and parallel thereto are two shafts "f" and "g." These shafts are in vertical alignment with each other and are suitably supported near each end in bearings provided in 55 upwardly extending portions of the frames "a" and "b." Shafts "f" and "g" serve as axial supports for circular cutters or saws "h" which are adjustably located on said shafts and form the slitting mechanism of 60 our machine. Shafts "f" and "g" are caused to rotate in unison by means of meshing spur gears "h'" located on the ends of the same, respectively, and approximately over the pulley "d." Shaft "f" bears upon its end 65 opposite gear "h'" a pulley "k" which latter is driven from pulley "e" by means of a belt "m."

From the description thus far given it will be readily understood that when main shaft 75 "c" is set in revolution, motion therefrom will be imparted by means of its pulley "e" through belt "m" to pulley "k" on shaft "f." Shaft "f" when in motion will, through spur gears "h'" on said shaft and the companion 80 shaft "g" impart in turn motion to said shaft "g," thereby causing the shafts "f" and "g" to revolve in unison.

The circular cutters or saws, mounted upon shafts "f" and "g," as already described, are 85 denoted by reference letter "n" and are preferably formed of suitable sheet metal. The cutters on shaft "f" are so located that their circumferential edges overlap those of shaft "g" to produce a shearing cut and the cutters 90 on each shaft are located a distance apart equal to the width of strip it is desired to cut, the cutters serving when revolving, as shown by the arrows of Fig. 1, to slit up a web of paper fed between the same into strips whose 95 width is regulated by the distance apart at which said cutters are adjusted.

Frames "a" and "b" are each provided at one end (the left hand as shown in the drawings) with journal bearings "a'" for the re- 100

ception of a spindle "b" which latter serves as an axial support for the roll of paper being operated upon. From the roll of paper thus supported the web is drawn forward to 5 the slitting mechanism, already described, after which operation the several strips pass on to be rewound or reeled into individual rolls, which rewinding mechanism we will now proceed to describe.

10 Near the right hand end of our machine, supported in suitable bearings, is located a spindle "p" having upon one end a pulley "p'" connected by belt "s" to the pulley "e" already referred to, the face of pulley "e" being sufficiently wide to receive both the belt "m" and also the belt "s." Belt "s" is normally so slack that no motion would be imparted thereby from pulley "e" to the pulley "p'" but to take up such slack, when it is desired 15 to set in revolution shaft "p," we have provided a belt tightener consisting of an ordinary foot lever "u" pivotally supported near the floor toward the right hand end of the machine. Foot lever "u" carries an idle 20 pulley "u'" to engage the belt "s" when the same is to be tightened. When foot lever "u" is rocked downward as shown in dotted lines (Fig. 1) it will be readily understood that pulley "u'" will be forced into contact 25 with the belt "s" thereby tightening the latter, and causing the same to impart motion from the pulley "e" to the pulley "p'" and its spindle "p" which, when set in revolution 30 will seek to wind upon itself the several strips 35 the ends of which have been previously suitably secured thereto. Said spindle "p" then serves to draw forward the several strips and cause the web of paper to unwind from the large roll. As soon as pressure is removed 40 from foot-lever "u" said lever at once drops by gravity to the position shown in Fig. 1, in full lines, the belt then again becoming slack and, as a consequence, stopping the re-winding 45 operation of the machine.

45 In order that the several strips may be tightly wound upon spindle "p" we have provided a bar "v" rounded and inclined upon its under surface to permit of the paper passing readily over it, and supported vertically 50 by arms "v'" secured to a rock-shaft "w" supported in frames "a" and "b." One edge of bar "v" engages the spindle "p," or the rolls of paper thereon, at or about the level of the center of said spindle and to cause said bar 55 to bear with considerable force against such spindle or rolls we have rigidly secured to the rock-shaft "w," one or more arms "w'," extending approximately at right angles to arms "v'" and bearing on their free ends 60 weights "x." By supporting the bar "v" trans-

versely of the machine in this manner, the supporting arms "v'" do not interfere with the strips of paper and the edge will press equally against the rolls of the rewound paper whether they are wide or narrow without any change 65 or alteration.

When it is desired to use a machine of our improved form a roll of paper is first placed in the bearings "a" and the end of the web is passed between the slitting knives "h" which cut and separate said roll into a multiple of narrow strips each of which is then passed under the bar "v" and finally secured to the spindle "p." When the machine is set in operation said strips are drawn forward and wound upon spindle "p," the bar "v" being meanwhile held forcibly against the circumferential faces of the several rolls creating a degree of tension sufficient to insure the compact rewinding of said strips. The several 75 strips are drawn tightly under the bar "v" and are thus prevented from "riding" upon each other and thus overlapping as they are rewound.

Having thus described our invention, we 85 claim—

1. In a slitting and rewinding machine, the combination, with a frame provided with a slitting mechanism, of a rewinding spindle and means for optionally revolving it, said spindle being adapted to have more than one roll of material wound upon it, a bar located transversely of the machine intermediate the slitting mechanism and the spindle and movable toward and from the spindle substantially in a line therewith, one end of which is rounded and inclined upon its under surface and means for causing said edge of the bar to bear against the rolls of material upon the spindle, substantially as set forth. 95

2. In a slitting and rewinding machine, the combination, with a frame provided with a slitting mechanism, of a rewinding spindle, frictional actuating mechanism for optionally revolving the spindle, a rock-shaft journaled 105 in the frame intermediate the slitting mechanism and the spindle, an arm rigidly secured to the rock-shaft adjacent each side the frame, a bar secured to said arms with its edge adapted to bear against the roll of material upon the spindle, and one of the arms being provided with an arm extending approximately 110 at right angles thereto, and having a weight upon its outer end, substantially as set forth.

REUBEN T. PALMER, JR.
